IONIZATION CHAMBER

Emilio G. Segre, Santa Fe, N. Mex., and Owen Chamberlain, Philadelphia, Pa., assignors to the United States of America as represented by the United States Atomic Energy Commission

Application December 13, 1945, Serial No. 634,864

4 Claims. (Cl. 250—83.6)

1

This invention relates to an improved ionization chamber.

A primary object of the invention resides in the provision of an improved ionization chamber adapted to increase the counting rate over prior art chambers, thereby resulting in increased efficiency of the device.

In certain nuclear physics experiments in which radioactive materials are to be measured, it is desirable to increase the counting speed of an ion chamber used to detect neutrons from a sample by increasing the effects produced by the slow neutrons directed into the chamber from an exterior source without changing the source of said neutrons. It is known to effectively increase the flux of thermal energy neutrons as measured by a chamber of known type by constructing the chamber of metals such as aluminum alloys which have low neutron absorption properties in place of metals of higher neutron absorption properties such as brass. While the use of an hydrogenous material such as polystyrene or paraffin for the purpose of scattering and reflecting or diffusing neutrons is known per se, such material having been commonly employed as a material in which ion chambers are enclosed or housed for the above stated purpose, the present invention employs such material in a novel manner, resulting in a substantial increase in the counting rate over known prior art devices of this general type.

A further object of the present invention is to provide an improved ion chamber wherein hydrogenous material performs the dual function of insulatingly supporting the various metal portions of the chamber while substantially filling the interior portion of the chamber to provide improved scattering, diffusing, and slowing of fast neutrons to thermal energies, the percentage of fast neutrons slowed to thermal energies to cause ionization in the present device being substantially larger than percentages heretofore obtained with prior art devices.

A still further object is to provide an ion chamber of improved design which has particular utility in obtaining quantitative measurement of the fissionability of radioactive samples, the chamber being subjected to slowed neutrons from a remote source of known strength or flux.

Further objects and advantages of the invention will become apparent to persons skilled in the art upon examination of the drawings, and the description, the inventive aspects of which are defined by the appended claims.

In the drawings, in which like parts are designated by the same reference numerals:

Figure 1 is a vertical diametric section of a device incorporating the present invention.

Figure 2 is a diametric section of the device of Figure 1 taken at 90° angularity to the section of Figure 1.

Figure 1.

Figure 3 is a rotated quarter-sectional view of the device of Figures 1 and 2, the sections of which are taken along lines 1-1, 2-2, 3-3, 4-4 of Figures 1 and 2.

Figure 4 is an enlarged fragmentary view of a marginal portion of the cathode assembly 42, Figure 1, for the purpose of illustrating constructional details of means for the detachable engagement of samples within the device.

5. Figure 5 illustrates the manner in which two of the devices are associated with a spaced neutron source, a sample of known material being placed in one chamber and a sample of unknown material placed in the other.

Referring to Figure 1, the device includes an inherently rigid metallic base plate 10 of circular configuration having suitably attached to the left face, as viewed, a flanged annular sleeve 11, interiorly threaded at 12 for mounting, preferably in the position shown, to an externally threaded supporting device, not shown. Base plate 10 and sleeve 11, as well as other metallic housing and supporting elements later described, with the exception of sample supporting plate, are preferably of metal having low neutron absorption properties, for example aluminum or aluminum alloy, or other suitable metal. Plate 10 also provides support for a cap-like closed end cylindrical housing 15 having at the mounted end thereof an integral annular flange 17 provided with an annular groove in which is disposed a resilient gasket 18. Gasket 18 is maintained in pressure engagement between plate 10 and flange 17 by means of a plurality of circumferentially disposed clamp screws 20 extending through suitable bores in flange 17 to threadedly engage hardened inserts 23 engaged in plate 10 in the manner shown.

Disposed within housing 15, in spaced relation to the side and closed end walls thereto, and in contiguous relation to the interior face of plate 10, is a hollow cylindrical element 25 of hydro-
genous material having good dielectric proper-
ties, such as "lucite," a methyl methacrylate
polymer. Element 25 is rigidly maintained by
clamping engagement with cylinder 26, also of
hydrogenous material, cylinder 26 being clamped
to plate 10 by a plurality of circumferentially
disposed clamp screws 28. A metallic cylinder
30, providing a guard ring, adapted to be

grounded, includes a relatively thick portion adjacent plate 10 and a portion of reduced thickness extending outwardly therefrom, cylinder 30 being interposed intermediate element 25 and cylinder 26. The assembly comprising element 25, cylinder 30, and cylinder 26 is maintained clamped by means of plural screws 32. A fluid conduit 34 extends through plate 10 to the interior of the device, which is otherwise sealed to the atmosphere. Conduit 34 leads through channel 38 to the volume between housing 15 and element 25, channel 37, Figure 2, leading therefrom to the volume defined intermediate element 25 and cylinder 26 to insure gas communication therebetween.

A pair of electrode assemblies 40 and 42 are mounted respectively on the free ends of inner cylinder 26 and outer cylindrical element 25 in the manner hereinafter described. As best shown in Figure 2, a circular plate 41, providing an anode, finds its support as follows: An annular metallic flange 44 is provided with a suitable number of integral lugs 45 for recessed engagement with complementary apertures provided in the end wall of cylinder 26, each such aperture having an aligned centrally threaded insert 47 imbedded in the hydrogenous cylinder material. A suitable clamp screw 48 extends through lug 45 to threadedly engage insert 47 and clamp flange 44 to the face of cylinder 26.

Flange 44 is further provided with multiple sockets 50 embedded in the material of cylinder 26, at points intermediate lugs 45, sockets 51 being adapted to detachably receive snap-in plugs 51, which are secured to plate 41 for the removable mounting thereof. Plate 41 is thus securely maintained within a complementary annular channel on the face of flange 44. The mounting assembly comprising sockets 50 and plugs 51 may be of a type well known in the radio art, for example, the General Radio type mount. Electrode plate 41 is detachably mounted as above to permit interchange between the laminated electrode plate, Figures 1 and 2, comprising an inner sheet of cadmium 55, contiguously disposed between a pair of outer sheets of "Duralumin" 56, and a solid "Duralumin" plate, not shown, for a purpose later described. "Duralumin" is an alloy of 93-95% aluminum, 3.5-4.5% copper, 0.5% magnesium, 0.25-1.00% manganese, with traces of iron and silicon.

As best shown in Figure 4, the cathode electrode assembly 42 includes an annular supporting flange 57 to which is clamped a circular copper plate 63 by multiple lugs 65 spaced circumferentially in respect to flange 57, as shown in enlarged detail, Figure 4. Plate 63 provides support for a platinum sheet 66, clamped thereto by brackets 67, to provide a base for the sample material 69, which may be electroplated to sheet 66 throughout the central area thereof. A cadmium plate 76 is detachably mounted to copper plate 63 to provide a shield for slow neutrons, later described. As shown in Fig. 1, the annular flange 57 is supported in the assembly by means of a marginally ribbed portion 58 imbedded in the end wall of element 25 and securely maintained therein by means of a plurality of clamp screws 59 which threadedly engage associated imbedded inserts 60, similar to insert 47, described above. A cylindrical cadmium sleeve 70 may be removably disposed within housing 15 to provide additional shielding to slow neutrons as described below.

Suitable electrical conduits extend from the electrode assemblies 40 and 42 to the exterior of

the device, cathode assembly 42 being connected by lead 68 through tube 36 and through a suitable glass seal 71. Anode assembly 40 is connected by lead 72, through suitable conduits 73 and 74, and glass seal 75.

Referring to Figure 5, a pair of the improved ion chambers, above described, designated 80 and 81, are disposed within opposite end portions of a block of hydrogenous material 83 enclosed within a lead shield 84. Chambers 80 and 81 are mounted on slidably mounted plugs 85 and 86, also of hydrogenous material to permit insertion and removal of the chambers within apertured end portions of block 83 to provide complete enclosure of the chambers by the block material. A source of fast neutrons 88 may be removably positioned midway between chambers 80 and 81 by rod 90, slidably associated within a vertical channel 91 provided in block 83. Source 88 is suitably attached to the lower end of rod 90. Lead blocks 94 and 95 provide protective shielding around the mouth of channel 91. Disposition of the components of the device are such that ion chambers 80 and 81 are subjected to the same magnitude of thermal energy neutron flux from source 88.

Operation of the device is as follows. With housing 15 and cathode plate 63 removed from both chambers, the laminated anode disc 41 is snapped into place, cadmium cylinder 70 inserted within housing 15, after which the sample carrying cathode disc 63 is mounted as above, with cadmium disc 76 attached, and housing 15 is replaced. A sample material of known fission rate is placed in one chamber, with a sample material to be measured placed in the other chamber. With a suitable known evacuating and fluid transfer apparatus connected to conduit 34, the device is pumped to approximately one millimeter of mercury and internally washed with argon in a known manner, after which argon is introduced to a pressure of one and one-half atmospheres. Conduit 34 is then suitably sealed and the associated apparatus disconnected. With the two chambers suitably mounted within the hydrogenous material as shown in Figure 5, and leads 68 and 72 of each chamber connected to individual counting circuits of a type known in the art, the apparatus is ready for operation.

Since the above device is primarily intended for recording the counting rate of fission due to slow neutrons, and since the observed fission rate is dependent to some degree upon the presence of fast neutrons, the percentage of fission due to fast neutrons may be accurately measured and subtracted from the total fission count in the following manner. It is known that cadmium is opaque to slow neutrons, hence by substantially enclosing the effective chamber area by cadmium shielding the fission count due to fast neutrons may be observed. This count is obtained with cylindrical shield 70, circular disc 76, and the anode assembly containing cadmium disc 55, in place as shown in Figure 2 and above described.

While this shielding does not present a complete barrier to the transmission of slow neutrons due to some leakage of neutrons marginally of disc 76 which may be diffused by the hydrogenous material within the counter, it has been empirically determined that this leakage factor is small in respect to the slow neutrons stopped by the cadmium. By interchange of samples between the chambers, errors due to small differences between the chambers are eliminated. Pursuant to obtaining the count without the cadmium shield, cylinder 70 and the disc 76 are removed and the

anode containing disc 55 replaced with the "Dur-alumin" anode and the count obtained which is due to fission caused by both fast and thermal energy neutrons. The count obtained by fast neutrons above is then subtracted from the count obtained by fast and slow neutrons to obtain a count due to the slow neutrons only. The independent recording devices mentioned may be electronic devices properly biased or otherwise adjusted to record counts above a predetermined threshold value.

Neutrons radiating from source 88 are largely slowed to thermal energies prior to entering the chambers 89 and 91. While a large percentage of fast neutrons are slowed by the block material prior to entering the chambers, the presence of a substantial amount of hydrogenous material within the chambers presented by elements 25 and 26 provides additional slowing means for neutrons entering the chambers at above thermal energies especially with the cadmium elements removed. Since the metallic components of the device other than plate 63 are of aluminum alloy or similar metal, neutron loss through absorption by the components of the device is relatively small. Neutrons impinging upon the sample 69 of each chamber cause fission which in turn causes ionization of the gas within the device. The number of ionization pulses appearing on the anode is indicative of the fission rate of the sample and since one such rate is known, the other is computed on a comparative basis.

We claim:

1. An ionization chamber having in combination, a metallic housing sealed from the atmosphere, an hydrogenous material disposed within said housing, said material filling a major portion of the volume therein, an ionizable gas maintained within said housing to fill the volume intermediate said hydrogenous material and said housing, a pair of electrodes mutually spaced within said housing and insulatingly supported from said housing by said hydrogenous material, means preventing the transmission of slow neutrons from a point exteriorly of said chamber to said hydrogenous material comprising protective elements opaque to the transmission of slow neutrons substantially covering said electrodes and the interior of said housing, a substantial portion of said electrodes being exposed to said ionizable gas, and means maintaining said electrodes at a difference of potential.

2. An ionization chamber comprising a hollow cylinder having one closed end and one open end, said cylinder being of low neutron absorbing material, a hollow cylinder of high neutron absorbing material adapted for removable disposition within said first cylinder, a closure element for the open end of said first cylinder, means for clamping said closure element in fluid sealing engagement with said first cylinder to seal the cylinder interior to the surrounding atmosphere, a solid cylinder of hydrogenous material concentrically disposed within the first cylinder and supported at one end on said closure element, means associated with the unsupported end of said solid cylinder for the removable attachment of a planiform electrode, a metallic guard ring circumferentially enclosing said solid cylinder, a hollow hydrogenous cylinder circumferentially enclosing said solid cylinder and said guard ring, means for clamping said hollow hydrogenous cylinder and said guard ring to said solid cylinder, said hollow

hydrogenous cylinder axially overlapping said solid cylinder at the unsupported end thereof, means associated with the overlapping end of said hollow hydrogenous cylinder for the detachable engagement of a second planiform electrode in parallel spaced relation to said first electrode, said detachable means permitting interchange between electrodes of low neutron absorbing properties and electrodes of high neutron absorbing properties, electrical conduit means associated with said electrodes and extending to the exterior of the chamber to permit application of a difference of potential therebetween, and means for maintaining an ionizable gas in the volume defined between said first mentioned cylinder and the assembly comprising the hydrogenous cylinders, the guard ring, and the electrodes, said guard ring being electrically connected to said closure element to permit grounding thereof.

3. An ionization chamber having in combination, a metallic housing sealed from the atmosphere, supporting elements of hydrogenous material disposed within said housing, said supporting elements filling a major portion of the volume therein, an inert gas maintained within said housing to fill the volume intermediate said supporting elements and said housing, a pair of electrodes in mutually spaced parallel relation within said housing and insulatingly supported from said housing by said supporting elements in a plane perpendicular to them, a substantial portion of said electrodes being exposed to said inert gas, a barrier element substantially opaque to the transmission of slow neutrons disposed within said housing between said housing and said hydrogenous material and surrounding said electrodes whereby slow neutrons radiating from at least one point exteriorly of said chamber are prevented from reaching said electrodes, and means maintaining said electrodes at a difference of potential.

4. An ionization chamber having in combination, a metallic housing sealed from the atmosphere, supporting elements of hydrogenous material disposed within said housing, said supporting elements filling a major portion of the volume therein, an inert gas maintained within said housing to fill the volume intermediate said supporting elements and said housing, a pair of electrodes mutually spaced in parallel relation within said housing and insulatingly supported from said housing by said supporting elements in a plane perpendicular to them, each of said electrodes including a removable metallic portion of substantially the same size as the electrode effective as a barrier against the transmission of slow neutrons through said electrodes into the space between said electrodes, a substantial portion of said electrodes being exposed to said inert gas, and means maintaining said electrodes at a difference of potential.
